United States Patent Office

Des. 195,016
Patented Apr. 9, 1963

195,016

CHECKOUT COUNTER

Arthur B. Sperry, Weston, and Paul H. Lee, Brookline, Mass., assignors to Sylvania Electric Products Inc., a corporation of Delaware

Filed Oct. 2, 1961, Ser. No. 66,952

Term of patent 14 years

(Cl. D80—2)

Des. 195,016

Fig. 3

Fig. 4

FIG. 1 is a perspective view taken from one side and the rear of a checkout counter embodying the new design;

FIG. 2 is a front perspective view taken from the side shown in FIG. 1;

FIG. 3 is a top plan view thereof; and,

FIG. 4 is an elevational view taken from the side opposite that shown in FIG. 1.

We claim:

The ornamental design for a checkout counter, as shown.
